INDENTING MACHINE

Filed June 20, 1922

UNITED STATES PATENT OFFICE.

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

INDENTING MACHINE.

Application filed June 20, 1922. Serial No. 569,676.

This invention relates to machines for use in the manufacture of boots and shoes and is herein illustrated as embodied in a machine for producing, as may be desired, 5 either a single or a double line of indentations along the seams or joints of rubber footwear.

In the process of manufacturing vulcanized footwear, such for example as arctics, the 10 adjacent margins of many of the parts are overlapped and pressed together while in the unvulcanized state to form the joints, very little if any thread being used to join any of the parts. After these overlapped 15 joints have been made it is customary to operate upon them by means of a hand tool comprising a handle having mounted in one end a so-called "stitching wheel"—a small thin wheel carrying on its periphery a series 20 of comparatively small teeth which form along the joint a line of indentations somewhat resembling a line of stitches. In some cases it is desirable to produce a single line 25 or row of indentations along one edge of the joint, and in others to produce a double row, one along each edge.

According to the present invention, this 30 operation is performed by power, and a single or double row of indentations may be produced at will. The illustrated machine 35 comprises a driven roll for feeding the work, a power driven indenting wheel and a second or auxiliary wheel which may readily be thrown into and out of operative position and connected or disconnected with the 40 source of power.

This and other features of the invention including certain details of construction and 45 combinations of parts will be described as embodied in an illustrative machine and pointed out in the appended claims.

Referring now to the accompanying drawings:—

Fig. 1 is a front elevation of a machine in 50 which the present invention is embodied;

Fig. 2 is an end elevation viewed from the left as shown in Fig. 1;

Fig. 3 is a detail in perspective of the treadle;

Fig. 4 is a plan view of the means for lock-

ing and unlocking the auxiliary indenting wheel, and

Fig. 5 is a perspective of the indenting wheels and the feed roll.

Mounted in an overhanging arm 9 which 55 is rigid with the frame 11 of the machine is a rotary shaft 13 having fast to its outer end a feed roll 15, said arm being provided at its outer end with a shelf 17 which co-operates with the feed roll in supporting the work. 60 Connected with the frame 11 in a manner which will presently be described is an arm 19 which overhangs the arm 9, said arm 19 having mounted therein a rotary shaft 21 having fast to its outer end an indenting 65 wheel 23. The arm 19 at its outer end has an upwardly extending bracket 25 to which is pivoted at 27 a bell-crank lever 29 at the lower end of the vertical arm of which is rotatably mounted an auxiliary indenting 70 wheel 31. In the bracket 25 is formed a segmental groove 32 the center of curvature of which is the axis of the pivot 27; and at each end of the groove is a socket one of 75 which is shown at 33 into either of which a locking pin 35 mounted in the horizontal arm of the bell-crank lever 29 may extend. A spring (not shown) tends to urge the pin 35 to the right as viewed in Fig. 1, so that whenever it is opposite one or the other of 80 the sockets 33, it will be projected into that socket and thereby hold the auxiliary indenting wheel 31 either in the operative position shown in Fig. 2 or in an inoperative position distant about 90°. In order to 85 withdraw the locking pin from whichever socket it happens to be projecting into, there is pivoted at 37 to the horizontal arm of the bell crank lever 29 a lever 39 the inner end of which is forked and extends beneath the 90 head of the pin 35, and the outer end of which is continually acted upon by a spring 40. With this construction, the operator may at any time press upon the outer end of the lever 39 so as to withdraw the locking 95 pin 35 from the socket and then swing the bell crank lever, together with the auxiliary indenting wheel 31 to move said wheel from operative to inoperative position, or vice versa. When the auxiliary wheel 31 is in 100

the position shown in Figs. 2 and 5, its axis is in alignment with the axis of the shaft 21 and the peripheries of the two wheels 31 and 23 are in register. The indenting wheel 23 is driven in the direction indicated in Fig. 5 and has projecting from its outer face a lug 41, which is located at the same distance from the axis of the shaft 21 as is a lug 43 on the inner face of the auxiliary wheel 31. 5 With this construction the auxiliary wheel 31 will be driven by the wheel 23, but may be moved from operative to inoperative position, in the manner described above, when desired. 10 The moving parts of the machine are driven from an electric motor 51 the shaft of which is connected by an Oldham coupling 53 with a worm 55, said worm meshing with a worm wheel 57 which is loosely mounted 15 upon a driving shaft 59, but may be clutched to that shaft at any time by depressing the toe of a treadle 61 and thereby pulling down upon a treadle rod 63 the upper end of which is pivoted at 65 to the horizontal arm of a 20 bell-crank lever 67, said bell-crank being in turn pivoted to the frame of the machine at 69. The details of this clutch mechanism have not been shown since they form no part 25 of the present invention and any suitable clutch mechanism may be employed. Fast to the shaft 59 is a wide gear 71 which meshes with an idle gear 73, said last-named gear meshing with a gear 75 which is fast to the shaft 21. The wide gear 71 also 30 meshes with a large gear 77 which is fast to the shaft 13. The shaft of the idle gear 73 is mounted in a bracket 81 which carries the overhanging arm 19 and is pivoted about the shaft 59. This bracket is urged at all times 35 to turn in a clockwise direction about the shaft 59 as viewed in Fig. 2 by a compression spring 83 in the following manner:

Extending downwardly from the bracket 40 is an arm 85 to which is pivoted at 87 a block 89 having a projecting cylindrical portion 91 which is received in one end of a headed sleeve 93 about which the spring 83 is coiled. Received in the headed end of the sleeve is the reduced inner end of a screw 45 95 which is threaded through the frame 11 of the machine and has at its outer end a hand wheel 97. The purpose of this construction is normally to hold the indenting wheels down in operative relation with the 50 feed wheel 15 and to permit the tension of the spring 83 to be varied, it being noted that a shoulder on the screw 95 contacts with the head of the sleeve 93.

In order to permit the indenting wheels to 55 be raised at any time so as to facilitate presentation of the work to the machine, a treadle rod 99 is pivoted to the bracket 81 so that when the heel end of the treadle 61 is depressed, the indenting wheels will be 60 raised.

Referring now to Fig. 3, the treadle rods 63 and 99 pass respectively through holes in the opposite ends of a bar 101 which is fastened by a set screw 103 to a shaft 105, the holes being of larger diameter than the rods, 70 and the rods having nuts at their lower ends one of which is shown at 106. The shaft 105 is rotatable in a bearing in a stationary member 107 and has fast to one end the treadle 61. With this construction, 75 depression of the heel of the treadle raises the indenting wheels and throws out the clutch; and depression of the toe of the treadle returns the indenting wheels to operative position and throws in the clutch. 80

In the operation of the machine, the heel of the treadle is depressed to raise the indenting wheel or wheels from the feed roll 15 so as to facilitate the presentation of the work. The toe of the treadle is then depressed whereby the indenting wheel or wheels are brought down upon the work and both the feed roll and the indenting wheels rotated. The operator guides the work in such manner that the row of indentations is 90 made along one edge of the seam or joint, in case a single row of indentations is desired, or along both edges of the joint if a double row is desired. The operator may at 95 any time adjust the bell-crank lever 29 so as to cause the machine to produce a single or a double row of indentations as may be desired.

Although the invention has been set forth 100 as embodied in a particular machine, it should be understood that the invention is not limited in the scope of its application to the particular machine which has been shown and described.

Having thus described my invention, what 105 I claim as new and desire to secure by Letters Patent of the United States is:—

1. A machine for forming a row of indentations in a piece of work having, in combination, a source of power, a rotary work supporting and feeding roll, an indenting wheel rotatable about an axis which is substantially parallel to that of the feed roll, means for moving the wheel into and out of operative relation to the feed roll, and means 110 for connecting the wheel with the source of power when the wheel is moved into operative relation with the roll and for disconnecting it from the source of power when the wheel is moved out of operative relation to the roll. 115

2. A machine for forming a row of indentations in a piece of work having, in combination, a source of power, a rotary work supporting and feeding roll, an indenting wheel rotatable about an axis which is substantially parallel to that of the feed roll, means for moving the wheel into and out of operative relation to the feed roll, and means 125 including a toe-and-heel treadle for con- 130

necting the wheel with the source of power when the wheel is moved into operative relation with the roll and for disconnecting it from the source of power when the wheel 5 is moved out of operative relation to the roll.

3. A machine of the class described having, in combination, means for feeding a piece of work and means for producing at will a single or double row of indentations 10 therein, said last-named means comprising an indenting tool, a source of power for actuating the tool, an auxiliary indenting tool movable into and out of operative position, and means for connecting and disconnecting 15 said auxiliary tool with the source of power.

4. A machine of the class described having, in combination, means for feeding a piece of work and means for producing at will a single or double row of indentations 20 therein, said last-named means comprising an indenting tool, a source of power for actuating the tool, an auxiliary intenting tool movable into and out of operative position, and means becoming operative when the 25 auxiliary tool is moved into operative position for connecting said tool with the source of power.

5. A machine of the class described having, in combination, means for feeding a piece of work and means for producing at will a single or double row of indentations 30 therein, said last-named means comprising an indenting wheel, a source of power for rotating the wheel, an auxiliary indenting 35 wheel movable into and out of operative position, and means for connecting and disconnecting said auxiliary wheel with the source of power.

6. A machine of the class described having, in combination, means for feeding a piece of work and means for producing at will a single or double row of indentations 40 therein, said last-named means comprising an indenting wheel, a source of power for rotating the wheel, an auxiliary indenting 45 wheel movable into and out of operative position, and means becoming operative when the auxiliary wheel is moved into operative position for connecting said wheel 50 with the source of power.

7. A machine of the class described having, in combination, means for feeding a piece of work and means for producing at will a single or double row of indentations 55 therein, said last-named means comprising two rotary wheels one of which is bodily movable into and out of operative relation to the work, and means for driving the bodily 60 movable wheel from the other wheel.

8. A machine of the class described having, in combination, means for feeding a piece of work and means for producing at will a single or double row of indentations 65 therein, said last-named means comprising two rotary wheels one of which is bodily

movable into and out of operative position in which its axis is alined with the axis of the other wheel, and lugs projecting from the adjacent faces of the wheels whereby the bodily movable wheel is driven from the 70 other wheel when the axes of the wheels are in alinement.

9. A machine of the class described having, in combination, a plurality of rotary tools, a rotary shaft to which one of the tools 75 is fastened, a lever by which the other tool is carried and a pivot for the lever so located that the axis of the last-named tool may be brought into alinement with that of the first-named. 80

10. A machine of the class described having, in combination, a plurality of rotary tools, a rotary shaft to which one of the tools is fastened, a lever by which the other tool is carried, a pivot for the lever so located 85 that the axis of the last-named tool may be brought into alinement with that of the first-named, and means for driving one tool from the other. 90

11. A machine of the class described having, in combination, a plurality of indenting wheels, a rotary shaft to which one of the wheels is fastened, a lever by which the other wheel is carried and a pivot for the lever so located that the axis of the last-named 95 wheel may be brought into alinement with that of the first-named. 95

12. A machine of the class described having, in combination, a plurality of indenting wheels, a rotary shaft to which one of the 100 wheels is fastened, a lever by which the other wheel is carried, a pivot for the lever so located that the axis of the last-named wheel may be brought into alinement with 105 that of the first-named, and means for driv- 105

13. A machine of the class described having, in combination, a work support, an arm overhanging the work support, a shaft rotatably mounted in the arm, an indenting 110 wheel and a gear fast to the shaft, a driving shaft rotatably mounted in the frame of the machine, a bracket by which the arm is carried, said bracket being pivoted about the axis of the driving shaft, a gear on 115 the driving shaft, and an idle gear carried by the bracket and meshing with the gear on the wheel shaft and with the gear on the driving shaft whereby the bracket may be swung about its pivot while maintaining the 120 gears in mesh. 120

14. A machine of the class described having, in combination, a source of power, a work support, an indenting wheel, a swing- 125 ing bracket by which the wheel is carried, a driving shaft, a treadle, and connections between the treadle and bracket and the treadle and driving shaft such that movement of the treadle in one direction moves the wheel to operative position and connects 130

the driving shaft with the source of power and movement of the treadle in the opposite direction moves the wheel to inoperative position and disconnects the driving shaft from the source of power.

15. The combination with means for feeding a piece of work, of means for operating simultaneously at will upon one or more localities of the work, said last-named means

comprising a tool, a source of power for actuating the tool, an auxiliary tool movable into and out of operative position, and means for connecting and disconnecting said auxiliary tool with the source of power.

In testimony whereof I have signed my name to this specification.

ANDREW EPPLER.
